UNITED STATES PATENT OFFICE.

STEPHEN PORTER, OF BOSTON, MASSACHUSETTS, ASSIGNOR TO MILTON A. KENT, OF SAME PLACE.

GLOVE-FASTENER.

SPECIFICATION forming part of Letters Patent No. 360,111, dated March 29, 1887.

Application filed December 10, 1886. Serial No. 221,163. (No model.)

To all whom it may concern:

Be it known that I, STEPHEN PORTER, a citizen of the United States, residing at Boston, in the county of Suffolk and State of Massachusetts, have invented certain new and useful Improvements in Glove-Fasteners; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention pertains to "ball-and-socket fasteners," so called, and may be considered as an improvement upon and intimately related to my invention as embodied in an application filed October 13, 1886, Serial No. 216,131, the essential feature of which consists in the employment of an eyelet with a shank imperforate and longitudinally corrugated in part.

My invention is contained in the socket member of the fastening, which, in lieu of being hemispherical, as generally constructed, and notched or cut to render the perimeter of its mouth yielding, is in the present instance made from a section of a cylinder, one end of which is closed and centrally perforated, while its opposite and open end is longitudinally corrugated. One-half the corrugations so formed project inwardly, and thereby contract the bore of the cylinder by double the depth of one corrugation. Thus by increasing the depth of the corrugations the mouth of the socket may be regulated in size, while the flexibility of the tube is effected thereby, more or less, according to the number of said corrugations.

The drawings accompanying this specification represent, in Figure 1, a central vertical section of a socket member of a fastening device; Fig. 2, a cross-section on line *y* *y* in Fig. 1, and Fig. 3 a view similar to that in Fig. 1 of a socket member of a fastening device secured to a fabric and embodying my invention. Fig. 4 is a central vertical section of a button-cap. Fig. 5 represents a modification in the button cap or fastening instrumentality, the stud being shown in broken lines.

In the annexed drawings, A represents the socket member of a fastening device adapted

to engage and retain the stud member when thrust within it. This socket member is preferably formed from a section of a hollow cylinder, which is to be cut of the requisite length and closed at one end—the upper—which is centrally perforated. When this stage in its manufacture has been reached, it is evident that the bore *a* is of uniform diameter throughout. To render the walls of the cylinder yielding, and at the same time contract the lower open end, I form a series of corrugations, *c c c*, longitudinally disposed, which extend only a short distance along the imperforate metal forming the socket member. By means of said corrugations the mouth of the socket is not only contracted and rendered less in diameter than the upper remaining part of the bore *a*, but it is likewise made flexible and yielding sufficient to readily admit the head of the stud and then close upon and hold the latter firmly in position when it is thrust within.

Having thus described the socket member proper and its peculiar construction and novel features, I will now proceed to explain the method of securing the same to a glove or other analogous article.

Since it is desirable to give the fastening, as an entirety, a neat and tasty appearance and cause it to approximate a button in shape, I have employed a button-shaped cap, B, (see Fig. 4,) struck up from some suitable material. This cap is centrally perforated, and is provided with a short tubular shank or boss, *b*, inwardly formed integrally therefrom, which serves as a fastening member. To firmly unite these two parts A B to the fabric, a perforation is made in the latter, and the fastening-boss *b* is thrust through it from the upper side. The socket member is now adjusted beneath the fabric, and the opening centrally formed in the closed end is now aligned with and receives said boss *b*. When the two parts are thus properly adjusted, pressure is applied and the extremity of the boss is upset and spread out upon the inside of the socket member, and the latter is completely and securely attached, as shown in Fig. 3.

An evident and simple modification is represented in Fig. 5, in which, in lieu of the fastening-boss *b*, integrally struck from the button-

cap, a simple fastening eyelet or rivet of some malleable metal may be employed. However, for economy in manufacture and strength of the article, I prefer the fastening-boss formed 5 integrally from the cap B, since by this method only two parts are required to form and attach the socket member to the material, in lieu of three or more pieces, as now generally employed.

10 I claim—

1. A socket member of a fastening device, composed of a hollow cup, the closed end of which is centrally pierced, while its open or mouth end is corrugated longitudinally and 15 thus rendered yielding, substantially as set forth.

2. A socket member of a fastening device, as described, composed of socket or cup A, with its longitudinal corrugations c c, and the button-cap B, provided with a boss, b, struck 20 therefrom, and by means of which the socket and button-cap are united together and secured to the fabric as an entirety, substantially as described.

In testimony whereof I affix my signature in 25 presence of two witnesses.

STEPHEN PORTER.
